(57) **CLAIM**

The ornamental design for a tissue holder, as shown and described.

DESCRIPTION

FIG. 1 is a top front perspective view of a tissue holder, showing our new design.

FIG. 2 is a bottom rear perspective view of the tissue holder.

FIG. 3 is a front elevational view of the tissue holder.

FIG. 4 is a rear elevational view of the tissue holder.

FIG. 5 is a left side elevational view of the tissue holder.

FIG. 6 is a right side elevational view of the tissue holder.

FIG. 7 is a top plan view of the tissue holder; and,

FIG. 8 is a bottom plan view of the tissue holder.

The tissue holder is shown with symbolic breaks in its length and width. The appearance of any portion of the article between the break lines forms no part of the claimed design. Features illustrated in broken lines form no part of the claimed design.
